Application July 1, 1937, Serial No. 151,394

3 Claims. (Cl. 101—126)

Our invention relates to improvements in printing apparatus, and particularly to that species used for reticulated screen process printing.

An object of our improvements is to combine with a platen a screen holder adjustably hinged to a basal frame for the platen, with means for relatively adjusting the platen upon the frame either longitudinally or laterally, and also likewise adjusting the platen to the screen holder.

Another object of our improvements is to provide devices for releasably locking the screen holder in a raised position.

Another object of our improvements is to furnish a plurality of resiliently controlled disappearing guide stops in apertured seats in the platen, of which one stop is mounted for longitudinal adjustments therealong.

Another object of our improvements is to supply manually actuatable means conjointly acting to lower said stop devices together while simultaneously unlocking the raised screen holder to permit its descent toward the platen.

Another object of our improvements is to provide means for even adjustments of the rocker screen holder to accommodate it to piles of stock of different thickness.

Other improvements will be more specifically alluded to and described hereinafter.

As various possible embodiments might be made of the above invention, and as various changes might be made in the embodiment above set forth, it is to be understood that all matter herein set forth or shown in the accompanying drawings is to be interpreted as illustrative and not in a limiting sense.

Fig. 1 is a top plan of our printing apparatus, with the major portions of the screen and screen holder broken away, both represented as in a lowered position. Fig. 2 is a bottom plan of the platen with certain portions of the mechanism mounted thereon and as dissociated from other elements thereof. Fig. 3 is a top plan of the frame and an auxiliary frame mounted thereon, with the platen, screen holder and some parts of the mechanism removed. Fig. 4 is a front elevation, with some medial parts broken away, of the adjustable screen holder supports and certain elements of the mechanism. Fig. 5 is a side elevation of certain portions of said supports and mechanism, while Fig. 6 is an opposite side elevation of the mechanism shown in Fig. 5. Fig. 7 is a detail elevation of one of the jointed post and arm devices included in the different means for adjusting the auxiliary frame and platen thereon longitudinally, and laterally, with parts broken

away. Fig. 8 is an enlarged cross section, with parts in elevation, of one of the two similar operating devices employed in resiliently returning the side stops to extended positions above the platen, the view showing one of the stops as extended normally above the platen, but the device shown being shown in an inverted position to conform to the showing thereof in said Fig. 2.

Like numerals of reference denote like elements throughout the several views.

This device is particularly designed for printing sheets piled upon the platen 3 including the use of a finely meshed silk or metallic wire screen 50 stretched and held tensionally and flatly in a screen holder 49 mounted hingedly on the rear part of the hollow frame 1. As the invention of this apparatus is devoted to the above use, no other or associated devices are shown herein, except as shown in the drawings and description thereof herein.

In the main frame, the side bars 1 are connected by end bars 38 and 39, with inner cross bars 4 and 5, spaced below the others. The upper or auxiliary frame 2 is mounted movably upon the main frame, their hollows in communication. Like cross-bars 30 and 31 in front and 35 and 36 at the rear, are secured on the lower face of the frame member 2 to project laterally and are loose on the side bars of the main frame, but seated under clip-bars 28 and 29 in front and 32 and 37 at the rear. The clip-bars are longitudinal, bowed and held by end screws. Thus the bars 30, 31 and 35 and 36 are held by the clip-bars, but the former may slide under the clip-bars adjustingly. The platen 3 is screwed at 48 at the corners of the frame 2.

By separate but similar means the frame 2 may be adjusted on the base frame 1 longitudinally, laterally or askew. A threaded stem 13 with knurled head 14 is seated in an interiorly threaded bearing member 13b mounted in the forward cross-bar of the frame 2, and has at its inner end a coned termination ending in a ball at 12 seated in a fitting cavity in the forward end of a longitudinal arm 11 having its rear part 11b bent downwardly and seated in a bearing hole 11c in an upwardly bowed medial part 9 of a plate 10 screwed at 8 to the bar 1. The screw 13 may be used to shift the frame 2 to and fro longitudinally. Like installations are provided on the right side of the frame 2 near front and rear ends to adjust it laterally or askew, to register it and the platen 3 with the screen holder above. These are shown respectively at 20, 21, 19, 18, and 17 and 16 on the bar 6, at the front. At the rear the corresponding

elements 26, 27, 25, 24, 23 and 22 are used for similar purposes, the plate 22 being on the bar 7.

In Fig. 7 is shown an alternative adjustment set, comprising like members 14a, 13, 13b, 11a, 11b, 5 and 10a apertured at 11c, except that the universal joint 12b with mounting in the furcations 12a are substituted for the said ball and socket joint.

As the transverse shaft 18 is bowed downwardly under the longitudinal shaft 11, there is no interference between them. The flexible arrangements above mentioned are such, that whether ball and socket joints as shown at 12 are used, or other mechanical equivalents such as the furcated joint shown in Fig. 7 are employed, all of 10 the adjustments of the frame 2 may be effected without binding either of these assemblies, so that any adjustments of the frame may be made as desired. As none of these adjustments are of 15 large extent, other uses of the platen connections or devices such as the arrangements of the disappearing stops 42, 44 and 46 and their operating means are not interfered with.

Set-screws 33 and 34 respectively clamp diagonally opposite clip-bars 32 and 29 to clamp releasably the lateral slide-bars 32 and 31 in any of adjusted positions to hold the frame 2 rigid in an adjusted position.

The screen holder 49 being mounted for vertical adjustments at either rear corner on the main frame 1 to the rear of the auxiliary frame 2, all these elements as above described may be associated in relative positions as above stated for working purposes.

Referring to Figs. 1, 4 to 6 inclusive, the screen holder 49 is shown as adjustably mounted at opposite rear corners. The mountings are alike, with base members 56—57 reversed in position. The standards 56 have threaded stems 60. The like parts 56 and 59 are spaced apart with knurled nuts 58 and 71 between them respectively, while like nuts 61 and 70 are also on said stems for locking purposes, the first pair for adjusting the bearing members 56 and 72 vertically, as engaged with faces of the bracket members 62 and 66 on the upper ends of the stems 60. By these means the screen holder may have either rear corner part adjusted separately as desired.

Laterally spaced bearing members 53 and 64 are rockably mounted on the elements 62 and 66 and are seated on the end parts of a shaft 63 whose opposite ends are fixed in the members 62 and 66, which latter are held in desired adjustments by the lock-nuts 61 and 70 respectively. The member 64 is kept from endwise shifting along the fixed shaft 63 by means of a ring held by a set-screw 65. The members 53 and 64 respectively (Figs. 1, 4, 5 and 6) have transverse bodies 52 fixed thereon traversed by the threaded stems 54 having thereon the stop nuts 55, and bodies 51 seat therethrough the opposite parts of the stems 54. The bodies 51 and 52 carry respectively the opposed jaws 51a and 52a, which as shown in Fig. 1 grasp the rear bar 49 of the screen holder clampingly.

Referring to Figs. 1, 4, 5 and 6, the left-hand body 52a has a forward cam-edged projection 73 with a notch 74 below the cam. A rearwardly bent arm 78 on the fixed body 66 has a depending swingable arm 77 pivoted at its upper end thereto, and a link 76 is pivotally connected to and between the arm 77 and the cam 73. A fixed hanger 79 on the body 66 has its lower end split and channeled to seat therethrough a corrugated bearing tube 88 traversed by a wire 89 whose rear end is connected to the lower end of the depend-

ing arm 77, and a set-screw 79a in the lower part of the hanger 79 acts to clamp the split parts thereof tightly upon the tube 88. As shown in Fig. 2, the tube 88 is below the level of the platen 3, and is carried thereunder through an aperture 5 not shown in the rear cross-bar of the auxiliary frame 2 as shown in full lines in Fig. 3, at 2a. 75 is a depending catch-arm hung swingingly upon the fixed member 66, having a toothed part 81 and swingable to at times ride on the edge of the 10 cam 73 and drop into engagement with the notch 74 therein, as a locking device. The lower part of the catch-arm 75 is connected by a coil spring 80 to the top of the main frame 1, tending to retain the tooth 81 in engagement with the cam 15 notch, as well as when riding upon the cam edge, yieldingly.

Referring to said Fig. 3, the numeral 85 denotes a longitudinal rock-shaft mounted near its opposite ends in apertured bearings as at 86 on the 20 main frame 1, and has at its forward end a crank arm 87 for manually rocking it. The rear end of the shaft 85 has a crank 83 with pin seated in a bearing hole in the bent link 82 which is connected pivotally at its opposite end to the lower 25 end of said arm 75. As shown in Figs. 4, 5 and 6, when the rock shaft 85 is normally rocked by the action of the spring 80 connected to the hanger 75, and link 62 with the rear crank 83, the hanger detent is engaged in the notch 74 of the cam 73, so 30 that the furcations 51a and 52a with the screen holder 49 are locked in a raised position to clear the platen 3. When the crank arm 87 is rocked outwardly, the above train of connections from the shaft 85 to the hanger 75 is moved in a direction to withdraw and unlock the detent 81 from the cam notch 74, so that the screen holder 49 drops downwardly toward the platen 3, placing the reticulated screen 50 in parallelism therewith.

When the screen holder is manually lifted the 40 hanger part 81 rides upon the cam edge until it engages the notch 74 again, under tensional action of the spring 80, and the rock-shaft 85 is returned to its outwardly rotated position shown in Fig. 3. By these means the screen holder may 45 be quickly raised and automatically locked, or lowered by rocking outwardly the shaft crank 87, which disengages the detent 81 from the cam notch 74.

Referring to Figs. 1, 2 and 8, in Fig. 1 the platen 3 has a relatively long longitudinal slot 40 near its left hand edge, seating therethrough a vertical bar stop 42 mounted for vertical movements at times to project above the platen 3, and at other times to disappear below the upper face of the platen, to clear it. This stop 42 is mounted slidably vertically in edge hollows 107a in a bearing body 107 beneath and slidably mounted longitudinally in a lateral slideway of spaced bars 3a mounted along the under face of the platen. Fig. 8, on a larger scale, shows the bearing member 107 as shown in Fig. 2 inverted.

A knurled head on a threaded stem has the latter mounted in a plate 114 alongside the upper bar of the pair 3a and this stem traverses loosely and is held by a sleeve stop thereon. The bar 114 has a spaced pair of arms 115 and 116, and the slideway 107 is connected between these arms and carries an oppositely directed arm 10 having a bearing aperture seating one end of a longitudinal rock-shaft 103. The slideway 107 has an arm 105, and on the shaft 103 an arm 103a is mounted having a terminal pin 103b passed through a slot 42a in the stop member 42 for free play therein. On the bearing portion of the arm 103a on a 75

squared part of the shaft 103 is a quartering arm 106 connected by a coiled tension spring 108 to the slideway 107.

Longitudinally spaced arms 95 and 96 are fixed by bolts to and between the side bars 3a in contact with the under face of the platen 3, and a cross connection between these arms includes a slideway like the other slideway 107, but fixed instead of adjustably mounted. The platen 3 has a bar stop 44 passed vertically and movably through an aperture 43 and like that shown in Fig. 8 inverted, an arm 99 being fixed on the shaft 103 having a like end pin passed through a slot in the stop 44, and a tensioning spring 109 is connected between the member 99 and the lower bar 3a. The stop 42 is movable to and fro longitudinally in the slot 40 adjustably, but the stop 44 which is longitudinally alined with it is not so movable. The springs 108 and 109 normally act upon these stops to project their upper parts above the upper surface of the platen 3.

There is provided a means for rocking the shaft 103 to tension the springs which act upon the aforesaid stops, as also a third stop 46 which is seated through a rectangular slot 45 in the platen 3, but being a head stop thereon for the upper ends of a pile of sheets which can be placed in contact at one side with the said stops 42 and 44. This third stop and its slideway is similar to that of the others as shown in Fig. 2, hence will not be further described.

The stop 46 is connected by means of a pin to one end of an arm 98 whose opposite end is pivoted to the cross-bar 96. An arm 102 is fixed on the rock-shaft 103 and carries a crank 110 having a pin traversing a medial hole in the arm 98. A wire link 101 is connected between the other end of the arm 102 and an adjacent end of a lever 91 which is pivotally medially mounted on a fixed support 92 being part of the member 94. The opposite end of this lever is connected to the wire 89 which traverses the curved bearing tube 88, and whose outer end (Fig. 5) is connected to the lower end of the depending arm 77, the latter medially pivoted to the link 76 which has its opposite end pivoted to the cam member 73.

By means of the aforesaid elements and connections, all three of the stops 46, 44 and 42 are simultaneously actuated, while tensioning the springs 108 and 109 when the wire 89 is drawn rearwardly to rock the lever 91 to oppositely pull in one direction the link 101, arm 102, thus rocking the shaft 103 with its arms 103a and 99, and also swinging downwardly the arm 98 to depress the stop 46. The above actions are initiated, when the above elements are set in train and movement as the shaft 85 is rocked outwardly by means of its crank 87 manually, its opposite crank 83 moving the connection 82 outwardly while tensioning the spring 80 and swinging the arm 75 also outwardly releasing the detent 81 from the cam notch 74, and the unlocked cam permitting descent of the screen holder 49. When the screen holder is then swung up, the cam rides over the detent 81 which the tensioned spring 80 acts to reengage the detent with the notch 74, to lock the screen holder as raised. The returning cam then by means of the above described connections

to the arm or lever 91, aided by release of tension of the springs 108 and 109, rocks the arms 42, 44 and 46 on the shaft 103, thus returning the stops to project above the platen, the apparatus being thus reset for the printing of another sheet on a pile positioned thereon in contact with the stops.

We claim:

1. In a device of the character described, in combination, a hollow basal frame, a hollow platen frame mounted movably thereabove, a platen fixed thereupon, supports fixed within and upon the basal frame, interiorly threaded bearings fixed across the front and one side member of the platen frame independently, set-screws mounted in said bearings and having diminished inner terminations, arms having socketed ends loosely fitting upon the inner terminations of said set-screws respectively and rockably mounted at their opposite ends upon said frame supports, arms fixed on the under faces of the forward and rear parts of the platen frame to project laterally therefrom across and upon the side parts of said basal frame, and clips secured to the basal frame and receiving therethrough the outwardly projecting portions of the platen frame arms, whereby either or all of said set-screws may be employed to adjust the position of the platen frame as desired upon the basal frame.

2. In a device of the character described, in combination, a basal frame, a platen frame positioned thereabove, threaded fixed standards mounted upon the rear part of the basal frame and spaced laterally apart, said standards each having and including a fixed U-shaped part having internally threaded vertically alined end bearings, screw shafts mounted through said bearings, nuts mounted upon said screw shafts within said U-shaped parts, a rock-shaft between and rockably mounted upon the top parts of said screw shafts loosely, nuts on the screw shafts movable to support the ends of the rock-shaft in independently adjusted positions, a screen-containing frame above said platen, clamping arms on said rock-shaft releasably clamped upon the rear part of the screen-frame, and means for manually releasably locking said rock-shaft in an elevated position.

3. In a device of the character described, in combination, a basal hollow frame, a platen hollow frame mounted adjustably thereupon, a screen carrying frame mounted upon the rear part of the basal frame adjustably above the platen frame, a platen removably mounted upon the platen frame, the platen having a slot alongside one edge thereof, and also having a transversely spaced pair of bearing apertures alongside the rear edge thereof, guides traversing said slots mounted for projection simultaneously above the platen or for subsidence below the upper face thereof, the guide in the side slot being also mounted for movements to and fro adjustably therealong, and manually operable mechanism mounted on and below the platen, flexibly separately interlinked with the guides resiliently, and also releasably interlocked with the screen carrying frame.

GLENN G. JOHNSON.
RAYMOND J. MALLER.
